(57) **CLAIM**

The ornamental design for a bed headboard ornament, as
shown and described.

DESCRIPTION

FIG. 1 is a front elevational view of a bed headboard ornament
showing my new design.

FIG. 2 is an enlarged front elevational view thereof.

FIG. 3 is a rear elevational view thereof.

FIG. 4 is a top plan view thereof; and,

FIG. 5 is a right-side elevational view thereof, with the left-
side elevational view thereof being a mirror image.

The broken lines in FIG. 1 show environment and form no
part of the claimed design.

The claimed design does not include any depth.
